SINGLE CONTROL CARRYING SCRAPER

Stanley S. Moore, Stockton, Calif.

Application January 30, 1935, Serial No. 4,064
Renewed April 8, 1937

18 Claims. (Cl. 37—126)

This invention relates to scrapers and particularly to carrying wheeled scrapers of what may be considered the medium size or general utility type—larger than the small Fresno or similar scrapers, but smaller than the scrapers used by large dirt moving contractors and which are very expensive and heavy and require a high power tractor for their operation.

The bowl of my scraper is movably suspended in a wheel supported frame for separate vertical movements both at its forward scraping edge and at its rear end; and one of the objects of my invention is to so mount the bowl that by the use of a single pull cable, the bowl may be successively moved from a scraping to a carrying position clear of the ground, and then tipped forwardly to discharge the load—all with a continuous movement of the cable in the same direction. The bowl is also arranged so that when the pull on the cable is released it drops of its own weight to a scraping position.

I also employ a front end gate or apron to cooperate with and close the front of the bowl when the latter is raised to a carrying position. A further object of my invention is to so mount this apron in connection with the bowl that as the latter is raised from a scraping to a carrying position by means of the single cable previously mentioned, the apron will automatically approach and engage the front of the bowl; while with a further upward movement of the bowl to a dumping position the apron will be both raised and at the same time retracted from the bowl.

The single cable operated from the tractor being all that is necessary to manipulate the bowl and cause the same and the apron to assume any desired position, as above outlined, the mechanism of the scraper is very simple and consequently its cost of construction is relatively low. The operation of the scraper is also greatly simplified since there is only the one cable drum to control, and the use of reversely driven cables which frequently tangle, or heavy return springs which increase the resistance and power necessary for operation, are eliminated.

A still further object is to so mount the bowl that it always tends to dig into the ground of itself without the use of any push-down mechanisms; the digging depth being controlled and maintained merely by holding the cable against slackening when the desired depth has been reached.

These objects I accomplish by means of such structure and relative arrangement of parts as

will fully appear by a perusal of the following specification and claims.

In the drawings similar characters of reference indicate corresponding parts in the several views:

Figure 1 is a side elevation of my improved scraper in its scraping position. 5

Figure 2 is a similar view partly in section showing the scraper in a carrying position.

Figure 3 is a side elevation showing the scraper in its dumping position.

Figure 4 is a fragmentary transverse section of the scraper taken on the line 4—4 of Figure 2.

Figure 5 is a fragmentary view showing a modified adjustable support for the apron pivot.

Figure 6 is a side view of the apron unit detached showing a modified mounting of the apron or its supporting arm. 15

Referring now more particularly to the characters of reference on the drawings, the frame of the scraper is preferably rectangular and includes side beams 1, inwardly of and supporting which are rear wheels 2 and a front swivel wheel truck 3. The truck 3 has a tongue 4 projecting forwardly therefrom and by means of which connection is made with the draw bar of a tractor. Each rear wheel is supported on opposite sides from bearings 5, the outer one of which is supported by the adjacent beam 1, and the inner one on a short longitudinal frame member 6. The frame members 6 of both rear wheels extend forwardly from the back cross beam of the frame 1 and are connected at their forward ends a short distance ahead of the bearings by a cross beam 7. 20

The bowl 8 disposed between the beams 1 and between the front and rear wheels is of any desired construction and is of substantially rectangular form in elevation, with a scraping blade 9 across its front edge and with its bottom rounded up into the back, as plainly shown. 30

The bowl is hung in the following manner:

Turnable on the rear wheel axles 10 are forwardly extending arms 11, which are pivoted at their forward ends on the back of the bowl near the bottom by a cross shaft or pins 12 mounted in ears E secured to the bowl. Between the rear wheels and the bowl the arms are rigidly connected by a cross bar 13 so that they must move simultaneously and possible twisting of the bowl is avoided. 40

Pivoted intermediate their ends, as at 14, on the beams 1 inwardly of the same adjacent the front end of the bowl when in its normal position are arms 15. The forward portions of these arms are rigidly connected to the sides of the apron 16 adapted to cooperate to form a closure 50 45 55

for the front lower portion of the bowl when said bowl and apron are in a certain position relative to each other as will be hereinafter set forth. The arms 15 rearwardly of the pivots 14 are provided with rigid upstanding extensions 17, the upper ends of which are pivotally and adjustably connected to the pins 12 by links 18. The links are here shown as being L-shaped, with the angular portion inverted and at the forward ends of the links, in order to clear the extensions 17 which they straddle in all positions.

The bowl is connected to the arms 15 by links 19 extending from pivots 20 on the bowl near the front lower edge of the same, to pivots 21 on said arms adjacent the base of the extensions 17. Extending from front to back of the frame and arching over the bowl is a centrally disposed hollow truss beam 22 preferably comprising a pair of channels placed in facing relation, as shown in Figure 4. This beam is braced from the main frame just back of the front wheels by diagonals 23 and by other diagonals 24 depending to the cross beam 7 which extends between the rear wheels.

A sheave block 25 is mounted in the beam 22 above the back of the bowl, and a similar block 26 is fixed on the back of the bowl centrally thereof and a short distance above the line of the pivots 12. A cable 27 extends from the tractor into the beam 22 adjacent its forward lower end and passes up to and about the sheave 25 over direction changing pulleys 28 enclosed in said beam. A very neat operating structure is thus provided. The cable depends clear of the beam at the sheave 25 and then passes about the sheave 26, being anchored on one of said sheaves. A pull on the cable therefore raises the bowl at its rear end.

When the bowl is in its digging position, as shown in Figure 1, the arms 11 have a downward slope toward their forward end, the links 19 are substantially vertical in depending relation to the arms 15, while the links 18 have a somewhat steep upward and forward slope. The pivots 12 are then below the line L drawn through the pivots 20 of the links 19 and the pivotal shafts 10 of the arms 11. As a result of this arrangement the scraper blade when once engaged with the ground has no tendency to lift out of the ground, but on the contrary will always dig in as deep as the slack on the cable will permit.

With all movements of the scraper from digging to dumping positions the pivotal point 12 of the arms 11 moves upwardly about an arc A centered at the axles 10; this arc first curving forwardly and then rearwardly, as shown in Figure 2. This feature is of importance in operating the scraper as will appear.

As the cable is pulled upwardly swinging the arms and bowl upwardly at its rear end, the links 18 which are connected to the pivots 12 are shifted toward a horizontal position. The forward end of the links 18 thus becomes shifted forwardly which causes the extensions 11 of the arms 15 to be also swung forwardly, the rear end of said arms raised and their forward ends lowered, said arms of course turning on the pivots 14. As a result the links 19 are raised, lifting the front end of the bowl while at the same time the apron is lowered toward the bowl. After a predetermined amount of such movement, the apron engages the front of the bowl closing the same while the pivot points 10, 12, and the pivotal connections C of the links 18

with the extensions 17 lie in a common or dead center alignment, as shown in Figure 2. The arms 11 and the links 18 have then reached their limit for forward movement.

With a further upward pull on the cable the pivots 12 swing upwardly but rearwardly, pulling the links 18 rearwardly also, which again raises the apron to adjacent its original position. At the same time the links 19, while being relatively lowered, are swung rearwardly due to the rearward movement of the bowl as a whole so that the front end of the bowl becomes raised but to a considerably lesser extent than its rear end. The bowl thus finally assumes the position in Figure 3, in which the bottom of the bowl is set at a steep slope so as to facilitate easy discharge; the front scraping edge is shifted a considerable distance rearwardly of its previous or normal position and is well above the ground so that ample discharge space between the apron and the front of the bowl and between the scraping edge and the ground is had.

The arms 11 are then disposed at a sharp upward angle, the links 18 (on a direct line between their end pivots) having a downward slope toward the front while the links 19 are substantially horizontal and face toward the rear. Upon releasing the pull on the cable the bowl drops of its own weight, at the same time of course restoring the various arms and links to their original positions due to the connection of the same with the bowl. As the scraping edge of the bowl engages the ground it will again dig in of itself to the depth permitted by the cable, as previously explained.

The central arch or truss beam which supports the cable sheave is sufficiently high to permit all necessary lifting of the bowl, while the diagonal braces 24 between said beam and the cross beam 7 of the main frame, transmit the strains had with the lifting of the bowl from said beam 22 to the main frame adjacent the wheels. Any tendency to bend the main frame with the lifting strains is thus eliminated and said frame may be made relatively light.

If it is desired to alter the normal slope of the bottom of the scraper, so that the bowl will enter the ground at different angles as the type of ground negotiated may require, it is only necessary to alter the point of connection of the links 18 with the pivots 12. This of course has the effect of swinging the arms 15, raising or lowering the links 19 and consequently the front end of the bowl correspondingly. At the same time the movement of the bowl to the different positions as previously described is not interfered with.

The same result may be obtained by mounting the pivots 14 of the arms 15 for vertical adjustment, as shown in Figure 5. In this case the pivots 14a are mounted in blocks 29 which are slidable in vertical yokes 30 secured to the side beams 1a. Adjustable screws 31 in the yokes hold the blocks in any set position.

If desired the apron may be mounted on its supporting arms in a manner to prevent possible breaking or distortion of any part in the event that rocks and the like are caught between the apron and the front of the bowl so as to prevent the proper closing of the apron. Such mounting of the apron is shown in Figure 6. In this case the sides of the apron 16a are shifted adjacent their rear end on the arms 15a, as shown at R. Compression springs 32 protected by enclosing housings 33 are disposed between the front

ends of the arms and the sides of the apron balance. In this manner the lip of the apron can yield upwardly or away from the bowl after the arms are lowered, preventing possible distortion 5 of the apron or its arms or damage to other parts.

From the foregoing description it will be readily seen that I have produced such a device as substantially fulfills the objects of the invention 10 as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

20 1. A scraper comprising a wheel supported frame, a bowl, arms pivoted on the frame behind the bowl and on the back of the bowl near the bottom, means applied to the back of the bowl to pull the same upwardly, means suspending the bowl from the frame near the front of the bowl, and means acting on the suspending means with the upward movement of the back of the bowl to also lift the front end of the bowl.

25 2. A scraper comprising a wheel supported frame, a bowl, arms pivoted on the frame behind the bowl and on the back of the bowl near the bottom, means applied to the back of the bowl to pull the same upwardly, means suspending the bowl from the frame near the front of the bowl, and linkage means between the suspending means and the back of the bowl arranged to pull up on the suspending means as the back of the bowl is lifted.

30 3. A scraper comprising a wheel supported frame, a bowl, arms pivoted on the frame behind the bowl and on the back of the bowl near the bottom, means applied to the back of the bowl to pull the same upwardly, rearwardly projecting arms pivoted on the frame adjacent the front 35 of the bowl, depending links pivoted on the rear end of the arms and on the bowl, and means between the arms and the back of the bowl to swing the arms upwardly as the back of the bowl is lifted.

35 4. A scraper comprising a wheel supported frame, a bowl, arms pivoted on the frame behind the bowl and on the back of the bowl near the bottom, means applied to the back of the bowl to pull the same upwardly, rearwardly projecting arms pivoted on the frame adjacent the front of the bowl, depending links pivoted on the rear end of the arms and on the bowl, rigid extensions projecting upwardly from the arms, and links pivoted on the upper ends of the extensions and projecting rearwardly and pivotally connected to the bowl at the back thereof.

40 5. A scraper comprising a wheel supported frame, a bowl, arms pivoted on the frame behind the bowl and on the back of the bowl near the bottom, means applied to the bowl to pull the same upwardly, and means supporting the bowl near its front end and including depending links pivoted on the bowl adjacent its forward end; a straight line drawn through the 45 pivotal connection of each link with the bowl and the pivotal connection of the corresponding arm with the frame lying above the pivotal connection of said arm with the bowl when the scraping edge of the bowl is in contact with the ground.

6. A scraper comprising a frame which includes side beams, spaced wheels inwardly of said beams adjacent the rear end thereof, bearing members for each wheel on both sides thereof, a bowl hung between the beams ahead of the 5 wheels, a central truss beam extending from end to end of the frame and arching over the bowl, lifting means between the back of the bowl and said truss beam above the back of the bowl, and transversely diagonal brace members extending 10 from the truss beam to connections with the frame adjacent the inner wheel bearing members.

7. A scraper including a wheel supported frame, a bowl hung therein, means applied to the bowl to lift the same from a scraping position to a carrying position and thence to a dumping position, an apron to cooperate with the front of the bowl mounted on the frame, and means connecting the apron with the bowl so that when the bowl is in scraping position the apron will 20 be clear of the bowl; when the bowl is raised to a carrying position the apron will be lowered to engage the bowl, and when said bowl is further raised to a dumping position the apron will be again raised to clear the bowl.

25 8. A scraper comprising a wheel supported frame, a bowl, means hanging the bowl in the frame so that with an upward pull on the back of the bowl the scraping edge of said bowl will first be raised from the ground a certain distance 30 without appreciable longitudinal movement and will then move rearwardly and upwardly but to a lesser extent than the movement of the back of the bowl, an apron mounted on the frame to cooperate with the bowl when the scraping edge 35 of the latter is in said certain position, and means connecting the apron with the bowl so that when the bowl is in a scraping position the apron will be held above and ahead of the scraping edge 40 of the bowl; when said edge is in said certain position the apron will be lowered to cooperate therewith, and when said bowl is further raised, the apron will be raised and held clear of the bowl.

45 9. A scraper comprising a wheel supported frame, a bowl, arms pivoted on the frame behind the bowl and on the back of the bowl near the bottom, means applied to the back of the bowl to pull the same upwardly, said arms having a downward slope to the bowl when the latter is in 50 a scraping position but swinging to assume an upwardly sloping position when the back of the bowl is swung upwardly to a dumping position, arms pivoted intermediate their ends on and extending lengthwise of the frame adjacent the 55 front of the bowl, an apron to cooperate with the front of the bowl supported by the last named arms in front of their pivot, links depending from and pivoted on the apron supporting arms rearwardly of the pivot thereof and on the bowl 60 below, extensions rigid with and upstanding from said apron supporting arms, and links pivoted on said extensions and on the bowl in common with said first named arms and disposed with an upward slope to the front when the bowl is in a 65 scraping position; whereby with the initial upward movement of the back of the bowl and said first named arms the last named links will shift toward a horizontal position and will impart a swinging movement to the apron supporting 70 arms in a direction to both lower the apron, and lift the front end of the bowl; the pivotal points of said last named links at both ends and the pivotal connection of said first named arms with the frame lying in common alignment when the 75

front of the bowl has been lifted a certain amount and the apron has been lowered to cooperate therewith.

10. A scraper comprising a wheel supported frame, a bowl, arms pivoted on the frame behind the bowl and on the back of the bowl near the bottom, means applied to the back of the bowl to pull the same upwardly, said arms having a downward slope to the bowl when the latter is in a scraping position but swinging to assume an upwardly sloping position when the back of the bowl is swung upwardly to a dumping position, an apron to cooperate with the front of the bowl, means supporting the apron from the frame, means connecting the bowl at the front and the apron supporting means so that as the apron is lowered the front end of the bowl will be raised, and means functioning with the swinging of the arms toward a horizontal position for thus lowering the apron to a bowl cooperating position; and also functioning with the swinging of said arms a predetermined amount beyond a horizontal position for then raising the apron clear of the bowl.

15. 11. A scraper comprising a wheel supported frame, a bowl, means applied to the back of the bowl to pull the same upwardly, an apron to cooperate with the front of the bowl, means movably supporting the apron from the frame, means connecting the bowl adjacent the front and the apron supporting means so that as the apron is lowered by the movement of its supporting means the bowl will be lifted at the front, and means functioning with the upward movement of the back of the bowl a certain amount to thus move said apron supporting means, so that the apron cooperates with the bowl.

12. A scraper comprising a wheel supported frame, a bowl, means applied to the back of the bowl to pull the same upwardly, an apron to cooperate with the front of the bowl, means movably supporting the apron from the frame, means connecting the bowl adjacent the front and the apron supporting means so that as the apron is lowered by the movement of its supporting means the bowl will be lifted at the front, and means functioning with the upward movement of the back of the bowl a certain amount to thus move said apron supporting means, so that the apron cooperates with the bowl, and also functioning with an upward movement of the bowl more than said certain amount to move and raise the apron clear of the bowl.

13. In a scraper having a frame and a vertically movable bowl therein, arms pivoted on the frame and projecting forwardly of the bowl, means to lower the arms at their forward ends as the forward end of the bowl is raised, an apron pivoted at its rear end on the arms to cooperate with the bowl when the arms are thus lowered,

and spring means between the arms and apron yieldably resisting upward movement of the lower edge thereof.

14. In a scraper having a frame and a vertically movable bowl therein, arms pivoted on the frame and projecting forwardly of the bowl, means to lower the arms at their forward end as the bowl is raised from a predetermined position, an apron to cooperate with the bowl when the bowl is thus raised and the arm is lowered, and means mounting the apron in connection with the arms so that the apron can yield upwardly a predetermined amount without a corresponding movement of the arms while causing the apron to be raised as the arms are raised.

15. A scraper comprising: a traction-supported frame; a digging bowl; lifting means, applied to the back of the bowl; supporting means for the front of the bowl; and means, other than the bowl itself, operatively connecting the back of the bowl to the supporting means, whereby the lifting of the bowl at the back operates to raise the scraping edge of the bowl, but to a lesser extent than the back of the bowl, so as to finally dispose the bottom of the bowl at a steep angle to the ground for dumping.

16. A scraper comprising: a traction-supported frame; a digging bowl; lifting means, applied to the back of the bowl; supporting means for the front of the bowl; and a linkage operatively connecting the back of the bowl to the supporting means, whereby the lifting of the bowl at the back operates to raise the scraping edge of the bowl, but to a lesser extent than the back of the bowl, so as to finally dispose the bottom of the bowl at a steep angle to the ground for dumping.

17. A scraper comprising: a traction-supported frame; a digging bowl; lifting means, applied to the back of the bowl; supporting means for the front of the bowl; means, other than the bowl itself, operatively connecting the back of the bowl to the supporting means; and means connecting the bowl to the frame whereby the resistance of the ground, during the forward movement of the frame causes a tendency, resisted and controlled by the lifting means, for the scraping edge of the bowl to descend.

18. A scraper comprising: a traction-supported frame; a digging bowl; lifting means, applied to the back of the bowl; supporting means for the front of the bowl; a linkage operatively connecting the back of the bowl to the supporting means; and means connecting the bowl to the frame whereby the resistance of the ground, during the forward movement of the frame causes a tendency, resisted and controlled by the lifting means, for the scraping edge of the bowl to descend.

STANLEY S. MOORE.
